UNITED STATES PATENT OFFICE.

SAMUEL GRADEN CARMACK, OF MADISONVILLE, KENTUCKY.

NUT-LOCK.

1,259,357.

Specification of Letters Patent. Patented Mar. 12, 1918.

Application filed July 17, 1917. Serial No. 181,123.

To all whom it may concern:

Be it known that I, SAMUEL GRADEN CARMACK, a citizen of the United States, residing at Madisonville, in the county of Hopkins and State of Kentucky, have invented a new and useful Nut-Lock, of which the following is a specification.

It is the object of this invention to provide a device of novel form, adapted to hold a nut against rotation, and to sustain against rotation, the washer wherewith the nut engages, novel means being provided for holding the nut locked on the material through which the bolt passes.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 shows in side elevation, a piece of material whereunto the structure forming the subject matter of this application has been applied;

Fig. 2 is a top plan of the device shown in Fig. 1;

Fig. 3 is a longitudinal section taken on the line 3—3 of Fig. 2;

Fig. 4 is a top plan of the nut lock, detached, one arm of the lock being broken away, and the washer being supported on the other end of the nut lock;

Fig. 5 is a perspective showing the working end of the nut lock, parts being broken away.

The nut lock forming the subject matter of this application is made out of resilient metal and is of approximately V-shape when viewed in side elevation, as disclosed in Fig.

1, the nut lock including an inner arm 2 and an outer arm 1. In the free end of the outer arm 1, a notch 3 is formed, the same

defining nut-engaging fingers 4, which may be offset slightly, as shown at 5, to facilitate the compression in the arm 1, as hereinafter described.

The inner arm 2 terminates at its free end in a reduced neck 6 carrying a tubular socket 7 disposed at right angles to the arm 2, the socket 7 being split as shown at 8, to add to the resiliency of the socket. In the inner arm 2, transverse slits 9 are fashioned, and the material set free by the formation of the slits 9 is bent over on top of the neck 6 to form tongues 10, the outer edges of the tongues constituting a shoulder 11, having 65 functions hereinafter described.

The numeral 12 denotes the material, having a bolt hole 14. The socket 7 is driven down into the bolt hole 14 and is held therein by friction, due to the expansibility 70 of the socket, the inner arm 2 resting on the material 14, in a way which will be obvious from Figs. 1 and 3. A bolt 15 is thrust through the bolt hole 14 and through the socket 7, the bolt fitting closely in the socket. 75 A washer 16 is placed around the bolt 15 and rests on the outer end of the socket 7, one edge of the washer engaging the shoulder 11, so that the washer cannot rotate.

The outer arm 1 then is pressed toward the arm 2 until the fingers 4 lie on each side of the washer 16 and below the upper face of the washer, presupposing that the bolt 15 is arranged vertically as shown in Fig. 3.

A nut 17 then is threaded onto the free end of the bolt 15. The nut 17 is turned by hand, as far as friction will permit, and then a wrench is applied to the nut. The wrench holds the arm 1 compressed and the fingers 4 depressed. The nut 17 is rotated

90 to a seat on the washer 16, by the wrench. The wrench is then removed, and the arm 1 will swing upwardly into the position shown in Fig. 3, the fingers 4 engaging the sides of the nut 17 and holding the latter against 95 rotation. The nut 17 and the washer 16 may, of course, be shaped as desired.

Having thus described the invention, what is claimed is:—

1. A nut lock comprising superposed inner and outer arms, the outer arm being resilient and being provided terminally with

nut engaging means, and the inner arm being provided with a projecting, tubular, bolt-receiving socket.

2. A nut lock constructed in accordance with claim 1, and further characterized by the fact that the inner arm is provided, adjacent the socket, with a transverse, washer-engaging shoulder.

In testimony that I claim the foregoing as my own, I have hereto affixed my signature in the presence of two witnesses. 10

SAMUEL GRADEN CARMACK.
